(57) CLAIM

The ornamental design for an antenna, as shown and described.

DESCRIPTION

FIG. 1 is a left-front perspective view of the ornamental design for the antenna.

FIG. 1A is an enlarged perspective view of the antenna taken from FIG. 1.

FIG. 1B is an enlarged perspective view of the antenna taken from FIG. 1.

FIG. 1C is an enlarged perspective view of the antenna taken from FIG. 1.

FIG. 2 is a right-rear perspective view of the ornamental design for the antenna.

FIG. 2A is an enlarged perspective view of the antenna taken from FIG. 2.

FIG. 2B is an enlarged perspective view of the antenna taken from FIG. 2.

FIG. 2C is an enlarged perspective view of the antenna taken from FIG. 2.

FIG. 2D is an enlarged perspective view of the antenna taken from FIG. 2.

FIG. 3 is a front view of the ornamental design for the antenna.

FIG. 4 is a rear view of the ornamental design for the antenna.

FIG. 5 is a left side view of the ornamental design for the antenna.

FIG. 6 is a right side view of the ornamental design for the antenna.

FIG. 7 is a top view of the ornamental design for the antenna; and,

FIG. 8 is a bottom view of the ornamental design for the antenna.

(Continued)

In these drawings, the features shown in broken lines depict environmental subject matter only and form no part of the claimed design.

1 Claim, 8 Drawing Sheets
